(57) **CLAIM**

The ornamental design for a footrest for car seat as shown and described.

DESCRIPTION

FIG. 1 is a perspective view of a footrest for car seat, showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a reference perspective view of the footrest for car seat shown in a configuration of use; and,

FIG. 9 is another reference perspective view of the footrest for car seat shown in another configuration of use.

The broken lines in the drawings are for the purpose of illustrating portions of the article that form no part of the claimed design.

1 Claim, 9 Drawing Sheets
